MITER BOX

William Owen, Pittsburgh, Pa., assignor to Pittsburgh Plate Glass Company, a corporation of Pennsylvania

Application April 6, 1935, Serial No. 14,987

4 Claims. (Cl. 143—87)

The invention relates to a miter box for use in cutting metal sash and the like, which is formed either from sheet metal or by extruded metal to form strips of the desired cross section. One object of the invention is to provide a cheap, simple construction having improved means for clamping the work in position and adapted to permit two strips to be mitered at the same time. Further objects are to provide improved means for setting the device to the desired angle of cut so that the adjustment may be made accurately and quickly, and for guiding the hack saw in a positive manner during the cutting operation. One embodiment of the invention is illustrated in the accompanying drawings, wherein:

Figure 1 is a plan view of the device. Fig. 2 is a section on the line II—II of Fig. 1. Fig. 3 is an end view of a part of the construction. Fig. 4 is an enlarged partial section on the line IV—IV of Fig. 1. Figs. 5 and 6 are detail views showing the blocks which are utilized in clamping the work in position. And Figs. 7 and 8 are detail views of the setting gauge which is employed in adjusting the device.

The base member of the device on which the work holder or deck is mounted for rotary adjustment comprises a pair of plates 1 and 2 in the form of a cross and on this base member are mounted the guides for the frame of the hack saw. These guides consist of the pairs of rectangular tubes 3, 3 and 4, 4 welded at their lower ends to the plate 1. Adapted to fit snugly between these pairs of posts is the frame of the hack saw. The frame consists of a top member 5 in the form of a rectangular tube and a pair of bottom members 6, 7 also in the form of rectangular tubes, secured together by means of the plates 7b and 7a welded to the ends of the tubes, and by the rectangular tubes 8 and 8a welded at their ends to the tubes 5, 6 and 7. The plate 7a is bent, as indicated at 9, in order to provide a handle, the rear portion of which carries the rounded wooden strips 10 to fit the hand of the operator. The hack saw 11 is secured at its front end to the frame by means of a pin 12 and at its other end is attached to a block 13 by means of the pin 14, the block 13 fitting slidably in the frame member 7. This block is adjusted to the rear to tighten the saw by means of the rod 15 which extends to the rear through the plate 7a and carries on its threaded rear end the wing nut 16. Stops for limiting the downward movement of the saw frame are provided in the form of the members 17 and 18 lying between the pairs of tubes 3, 3 and 4, 4 and welded thereto, such stops

being provided at their forward edges with saw cuts 19 which act as a guide for the gauge used in connection with the apparatus, as later described.

The work holder or deck which is mounted for rotary adjustment on the base member comprises a plate 20 having a hub 21 at its center and the flanges 22 and 23 on each side of the hub. Extending to the right from the flange 23 is the arc-shaped extension 24 provided on its edge 10 with the graduations 25 (Fig. 1) to show the degree of rotary adjustment of the deck with respect to the base member. Extending through the hub 21 of the deck is the hollow stud or pivot 26 which is welded to the base member and has threaded to its upper end the securing nut 27 for holding the base member and deck in assembled relation, but at the same time permitting rotary adjustment of the deck with respect to the base member. The opening 28 through the stud 26 is to permit of the attachment to the deck of the setting gauge, later described in detail. The deck is secured in its various positions of rotary adjustment by means of the clamping plate 29 through which extends a stud 30 welded at its lower end in the plate 1 of the base member. The upper end of the stud is threaded and carries the wing nut 31. The end of the clamping plate extends between the guide posts 4, 4 and over the graduated edge of the arc-shaped extension 24, as indicated in Fig. 2. The end of the clamping plate is provided with an indicating mark 32, preferably formed by making a saw cut in the end of the plate. This registers with the graduations 25 and indicates the degree of angular adjustment of the deck with respect to the base member.

Extending across the plate 20 is a vertical rib 33 provided at its center with a slot 34 in alignment with the guide spaces between the posts 3, 3 and 4, 4, the purpose of the slot being to permit the movement of the hack saw downward without interference with the rib. In the operation of cutting strips, such as the strip A, which constitutes the work, such strips are clamped in the angle between the rib and the deck. Secured to the plate 20 by means of bolts 35 is a wood sheathing 36. This sheathing stops short of the flanges 22 and 23 at each edge, as indicated in Figs. 2 and 4, and is cut out so as to form the L-shaped slots 37. The purpose of these slots is to provide for the engagement of the lower edges of the work clamping bars 38 shown in Fig. 2. The lower end of the bar 38 fits into the slot 37, while its upper end 40 hooks over the

upper edge of the rib 33. One or more of these clamping bars may be used and they are applied by placing them at the ends of the rib 33 and slot 31, and then slipping them laterally longitudinally of the rib to the desired position. The direct clamping element for the work comprises the threaded stud 41, which extends through the inclined portion of the bar and through the nut 42 which is welded to the bar. By rotating the stud, the work can be securely clamped into the angle between the rib 33 and the deck. In order to facilitate this clamping action without injury to the strips to be cut, various forms of wood blocks may be employed as indicated in Figs. 5 and 6. As here shown, the strip A to be cut is a section of sash bar of the extruded type and its inner edge is supported upon a wood block 43, which rests upon the sheathing 36 with its vertical side in engagement with the rib 33. A wood block such as the block 44 is placed upon the top of the strip A and is engaged by the stud 41 to give the necessary clamping action. The strip A is thus securely supported during the sawing operation without injury to its surface.

The strips to be sawed may be clamped on either or both sides of the rib 33, and if desired, two strips may be cut at the same time. The deck may be rotated about its pivot 26 so that the saw 11 will lie at any desired angle with respect to the work carried upon the deck, the relation between the saw cut 32 and the graduations 25 indicating accurately the angle of adjustment. As shown in Fig. 1, the device is set so as to cut at an angle of 30 degrees to the center line B—B of the deck.

Figs. 7 and 8 illustrate the setting gauge which is employed to advantage in adjusting the miter box to the desired angle. As appears later, the setting gauge can be placed in the angle for which the miter is to be cut and clamped in position, after which it can be applied to the miter box and the deck rotated until the rib 33 occupies the proper position as determined by the gauge. When the deck is clamped in position, the box is ready to receive the work, and the cut may be made. The gauge comprises a sleeve 45, in which is mounted for free sliding movement the pointer 46, such pointer having its outer end 47 brought to a sharp point and its inner end 48 turned at right angles and adapted to fit snugly in the perforation 28 through the pivot 26 of the deck (Fig. 4). Welded to the end of the sleeve is a bracket 49, to which are pivoted the arms 50, 50. Slidable on the sleeve is a cross head 51, and the pairs of similar links 52, 52 are pivoted at their inner ends to this cross head, and at their outer ends to the arms 50, 50, as shown. The cross head carries a clamping bolt 53 so that, when the cross head is brought to its desired position, it may be clamped in such position, thus securing the arms 50, 50 in fixed angular relation.

In using the setting gauge, the device is placed in the corner for which the miter is to be cut, and the cross head 51 is adjusted until the two arms 50, 50 touch the walls constituting the boundaries of the corner, at which time they are fixed in position by screwing in the bolt 53 which locks the cross head in position. The gauge is now laid upon the deck of the miter box and the end 48 of the pointer is inserted into the perforation 28, the outer end 47 of the pointer being positioned on the deck so that it comes in line with the saw cut 19 (Fig. 1). The gauge is held in this position while the deck is rotated

until the rib 33 contacts with the outer side of one of the arms 50 throughout its length, after which the clamping nut 31 (Fig. 2) is screwed down to clamp the deck in its adjusted position with respect to the base member. This gives the correct angle for mitering to correspond to the angle between the arms 50, 50. For example, if this angle happened to be 60 degrees (as shown in Fig. 7) and the procedure above given were followed, the graduation indicating 30 degrees would come exactly opposite the saw cut 32 (as shown in Fig. 1) when the adjustment had been completed. The gauge thus permits of the accurate adjustment of the miter box to any angle without the necessity of measuring such angle, and the operation may be carried out very quickly in any case in which it is possible to thrust the gauge into the angle which must be bisected in cutting the miter.

What I claim is:

1. In combination in a miter box, a base member provided with vertical guide means for a saw, a unitary work supporting deck mounted on the base for adjustment about a vertical axis, a vertical rib extending across the deck rigid therewith in line with said vertical axis with a slot at its central portion in line with such axis and with said guide means, and means for clamping the work to be cut against the deck and against said rib, and comprising a locking slot in the deck in parallel with the rib but spaced away therefrom, an inclined bar having hook ends, one of which lies in said slot and the other of which hooks over the top of the rib, said bar being slidable longitudinally of the slot and the rib, and a clamping stud carried by said bar and adapted to press the work into the angle between the rib and deck.

2. In combination in a miter box, a base member provided with vertical guide means for a saw, a unitary work supporting deck mounted on the base for adjustment about a vertical axis, a vertical rib extending across the deck rigid therewith in line with said vertical axis with a slot at its central portion in line with such axis and with said guide means, and means for clamping the work to be cut against the deck and against said rib, and comprising a locking slot in the deck in parallel with the rib but spaced away therefrom, an inclined bar having hook ends, one of which lies in said slot and the other of which hooks over the top of the rib, said bar being slidable longitudinally of the slot and the rib, and a stud threaded through said bar at an angle of about 45 degrees with respect to the rib.

3. In combination in a miter box, a base member provided with vertical guide means for a saw, a work supporting deck mounted on the base for adjustment about a vertical axis, a vertical rib extending across the deck in line with said vertical axis with a slot at its central portion in line with such axis and with said guide means, means for clamping the work to be cut in the angle between the deck and rib, means at the axis of rotation of the deck for releasably interlocking with a setting gauge pointer, and a setting gauge comprising a sleeve, a pointer slidable through the sleeve and provided at its inner end with means for interlocking with said means at the axis of rotation of the deck, a pair of arms on opposite sides of the sleeve pivoted at their inner ends to the inner end of the sleeve, a cross head slidable mounted on the sleeve, a pair of links pivoted to the cross head at their inner ends and to the

arms at their outer ends, and means for locking the cross head in adjusted position on the sleeve.

4. In combination in a miter box, a base member provided with vertical guide means for a saw, a work supporting deck mounted on the base for adjustment about a vertical axis, a vertical rib extending across the deck in line with said vertical axis with a slot at its central portion in line with such axis and with said guide means, means for clamping the work to be cut in the angle between the deck and rib, a vertical recess at the axis of rotation of the deck, and a setting gauge

comprising a sleeve, a pointer slidable through the sleeve and provided at its inner end with a part at right angles thereto adapted to fit into said recess, a pair of arms on opposite sides of the sleeve pivoted at their inner ends to the inner end of the sleeve, a cross head slidably mounted on the sleeve, a pair of links pivoted to the cross head at their inner ends and to the arms at their outer ends, and means for locking the cross head in adjusted position on the sleeve. 10

WILLIAM OWEN.
